United States Patent Office

Des. 185,730
Patented July 28, 1959

185,730

ENCLOSED SPOOL FISHING REEL

Richard E. Beger, Jersey City, N.J., assignor to The Lionel Corporation, New York, N.Y., a corporation of New York

Application June 30, 1958, Serial No. 51,600

Term of patent 14 years

(Cl. D31—4)

FIG. 1.

FIG. 2.

Des. 185,730

PAGE 2

Fig. 5.

Fig. 1 is a rear perspective view of an enclosed spool fishing reel showing the new design;

Fig. 2 is a left side elevational view thereof;

Fig. 3 is a front elevational view thereof;

Fig. 4 is a top plan view thereof; and

Fig. 5 is a bottom plan view.

I claim:

The ornamental design for an enclosed spool fishing reel as shown.
